(57) **CLAIM**

The ornamental design for a closure for containers, as shown and described herein.

DESCRIPTION

FIG. 1 illustrates a front perspective view of a closure for containers;

FIG. 2 illustrates a top view of the closure for containers of FIG. 1;

FIG. 3 illustrates a bottom view of the closure for containers of FIG. 1;

FIG. 4 illustrates a cross-sectional view of the closure for containers of FIG. 1; and,

FIG. 5 illustrates a side view of the closure for containers of FIG. 1.

The broken lines in the drawings depict environmental subject matter only and form no part of the claimed design.
